UNITED STATES PATENT OFFICE.

ALFRED N. PARNALL, OF FLORENCE, COLORADO.

CENTRIFUGAL PUMP.

No. 921,624.

Specification of Letters Patent.

Patented May 11, 1909.

Application filed October 7, 1907. Serial No. 396,287.

To all whom it may concern:

Be it known that I, ALFRED N. PARNALL, a citizen of the United States, residing at Florence, in the county of Fremont and State of Colorado, have invented a new and useful Centrifugal Pump, of which the following is a specification.

This invention relates to centrifugal pumps, and has for its principal object to provide an improved construction of pump in which the revoluble piston blades serve to force the water outward to an annular space between the periphery of the piston and the inner circular wall of the cylinder, this space being in free communication with the discharge.

With this and other objects in view, as will more fully hereinafter appear, the invention consists in certain novel features of construction and arrangement of parts, hereinafter fully described, illustrated in the accompanying drawings, and particularly pointed out in the appended claims, it being understood that various changes in the form, proportions, size and minor details of the structure may be made without departing from the spirit or sacrificing any of the advantages of the invention.

In the accompanying drawings:—Figure 1 is a sectional perspective view of a centrifugal pump constructed in accordance with the invention. Fig. 2 is an elevation of the pump with the outer section of the casing detached. Fig. 3 is a transverse sectional view of the pump.

Similar numerals of reference are employed to indicate corresponding parts throughout the several figures of the drawings.

The pump is mounted on a suitable base and the cylinder is formed of two main castings 10 and 11 that are provided with bolting flanges 12, secured together by bolts in the usual manner.

The section 10 of the casing is provided with supporting feet 13 which are firmly secured to the foundation, and the central portion of this section 10 is provided with an elongated hub 15 that is bored out to form a bearing for a shaft 16 that may be driven in any suitable manner. The hub is provided with a suitable stuffing box 17 and gland nut 18 in order to prevent leakage of water past the shaft.

Secured to the end of the shaft is a revolu-

ble piston 20 having a plurality of blades 21, the blades curving outward from the center to the periphery, and being so disposed that their convex faces act on volumes of water or other fluid entering at the center and 60 such fluid will be propelled with great force toward the periphery of the piston, the fluid passing into the annular space 2 that is formed between the periphery of the piston and the blades.

The section 11 of the casing is provided with a centrally disposed opening 23, forming an inlet for the water, or other fluid, and is, also, provided with an outlet 24, there being a bolting flange at the mouth of the outlet to 70 permit connection with a suitable pipe through which the water or other fluid is conveyed to the point of consumption.

In the section 11 is formed a partition 26 that divides the inlet from the discharge 75 chamber 27, this discharge chamber being annular in form and communicating with the outlet 24. The partition 26 is arranged on a curved line extending gradually from the inlet up to a point coincident with the periphery of the piston, so that the water inlet gradually diverges from the inlet end toward the piston, and there is no obstruction to the flow of the water to the piston. The diameter of the partition 26 is the same as the diameter of the piston; and that edge of the partition which faces the discharge chamber 27 is curved so as to offer minimum resistance to the passage of the water from the annular space of the cylinder over the edge of 80 the partition and down into the annular discharge chamber 27.

In practice the water will enter through the opening 23, and will be acted upon by the blades 21, each blade taking its quantity of 95 water or fluid and independently forcing the same out to the annular space of the cylinder. As the water reaches this annular space under a pressure dependent upon the speed of the pump, its flows in an annular stream 100 into the annular discharge chamber 27, and being under pressure is forced through the outlet 24 in a continuous unbroken stream.

It will be observed that the pump differs materially in its construction and operation 105 from that class of pumps in which the discharge is peripheral. In this latter class of pumps, the water that is forced by the piston blades to the periphery of the piston must be carried around in frictional contact with the 110

circular wall of the cylinder until it arrives at the discharge, the discharge being usually in a line tangential to the piston.

While the pump has been described as a water pump, it may, of course, be used for pumping liquids of any kind and may be used, also, as a fan or blower for forcing air or other fluid.

I claim:

- 10 1. In a centrifugal pump, a casing consisting of two sections, a piston working in one of the sections, with the outer ends of the blades spaced from the inner periphery of said section, whereby an annular space surrounding the piston is had, and an annular wall in the other section forming an inlet, said wall being flared at its inner end, and extending up to the outer ends of the piston blades, and said wall forming an annular discharge chamber concentric to and communicating with the aforesaid annular space around the piston, and said discharge chamber having an outlet.
- 15 2. In a centrifugal pump, a casing consist-

ing of two sections, a piston working in one of the sections in contact at one side with its end wall, and with the outer ends of its blades spaced from the inner periphery of said section, whereby an annular space surrounding the piston is had, and an annular wall in the other casing section forming an inlet, said wall being flared at its inner end and extending up to the outer ends of the piston blades, and said wall forming an annular discharge chamber concentric to and communicating with the aforesaid annular space around the piston, the wall of said space being curved in the direction of the discharge chamber, and said discharge chamber having an outlet.

In testimony that I claim the foregoing as my own, I have hereto affixed my signature in the presence of two witnesses.

ALFRED N. PARNALL.
